[57] CLAIM

The ornamental design for a luggage and cargo container body, as shown and described.

DESCRIPTION

FIG. 1 is a perspective view of the luggage and cargo container body showing our new design;

FIG. 2 is a top plan view thereof;

FIG. 3 is a rear elevational view thereof;

FIG. 4 is a bottom plan view thereof;

FIG. 5 is a left side elevational view thereof, the right side being a mirror image of the left shown;

FIG. 6 is a front elevational view thereof; and,

FIG. 7 is a reduced perspective view of the luggage and cargo container body with the lid in a raised position.
